CORRUGATED BUILDING MATERIAL

John E. Ochiltree, Wheaton, Ill., assignor to Ceco Steel Products Corporation, Omaha, Nebr., a corporation of Nebraska

Filed June 12, 1958, Ser. No. 741,505

2 Claims. (Cl. 50—243)

This invention relates to building material and more specifically to corrugated sheet material designed for use as roofing and capable of use also as siding or sheathing.

The present invention constitutes an improvement upon prior patent to Ned A. Ochiltree, No. 2,781,877, issued February 19, 1957.

In the commercial use of the invention disclosed in said patent it has been discovered that, unless the sheets are carefully laid and the corrugations of the overlapping margins are accurately aligned or fitted together, the mastic sealing material which is interposed between the lapped portions of the sheets sometimes fails to entirely close and seal the space between the sheets. Such failure, when it occurs, is usually at the crest of an underlying corrugation where a small unsealed opening is left through which moisture may eventually creep by capillary action so as to gain entrance to the interior of the building structure.

The primary object of my present invention is to provide a seal between lapped corrugated sheets which will insure against the leakage of moisture through a roof or siding.

Another purpose of my invention is to obviate the possibility of the above described leakage without substantially increasing the cost of production of the sheathing or roofing material.

A still further object is to provide a nailing line for the application of roofing in the field by the same structure or formation of the sheet which performs the desired sealing function.

Other objects and advantages of my invention will be appreciated as the same becomes better understood by reference to the following description when considered in connection with the accompanying drawing.

Referring to the drawing,

FIGURE 1 is a fragmentary plan view of the overlapping lower margin of a roofing or sheathing strip;

FIG. 2 is a fragmentary plan view of the underlapping upper margin of the same or a companion sheet;

FIG. 3 is an enlarged fragmentary sectional view illustrating in exaggerated form the point of leakage resulting from carelessly laid sheets;

FIG. 4 is an enlarged fragmentary sectional view on the line 4—4 of FIG. 1;

FIG. 5 is an enlarged fragmentary sectional view on the line 5—5 of FIG. 1;

FIG. 6 is a fragmentary sectional view of a lapped joint embodying my invention; and

FIG. 7 is an end view of the upper edge of FIG. 2.

Referring to the drawing more in detail, reference character 6 indicates generally a corrugated sheet of metal or the like such, for instance, as is disclosed in said Patent No. 2,781,877, and having major corrugations 6a of substantial depth and width (FIG. 7). The upper and lower margins of such sheets are provided with small corrugations of lesser depth and width than the major corrugations 6a, as shown. The marginal corrugations of the overlapping sheet are designated by reference character 7 (FIG. 1) and similar corrugations of the underlapping sheet are designated by reference character 8. It will be understood, of course, that each strip or sheet is corrugated along both the upper and lower margins. In other words, the lower overlapping margin of the sheet 6 is provided with the corrugations 7 while the upper under-

2

lying margin of the same sheet is provided with similar corrugations 8.

5 The underlying margin of each sheet is provided with a strip or band 9 of suitable sealing material, such as mastic which is plastic in character so as to be capable of being compressed between the lapped margins to fill the intervening space and provide a weather-proof seal. To prevent injury to the mastic strip and prevent the mastic from sticking to objects with which it might come in contact in handling and shipment, the outer face of the strip is covered with a strip of paper (not shown) which is removed by the applicator before the strip is laid.

10 It will be obvious that the best sealing effect will be obtained between the lapped corrugated margins when the corrugations 7 and 8 are accurately aligned, thereby providing spacing of uniform thickness between the lapped margins. In practice, however, the applicators sometimes become careless in laying the sheets with the result that the crests and valleys of the lapped sheets do not accurately align. FIG. 3 of the drawing illustrates to an exaggerated degree the condition which may result from such failure to align the lapped corrugations. As shown in FIGS. 3 and 6, the overlapping corrugations 7 are not accurately aligned with the underlying corrugations 8, 15 consequently, the intervening space between the sheets in which the mastic sealing material 9 is disposed is of varying thickness with the maximum space occurring beneath the overlapping crests of the corrugations. The result is that small openings 11 unfilled by the sealing material are sometimes left, which permit moisture to enter by seepage or capillary action between the lapped sheets into the interior of the building structure.

20 To obviate such leakage is the purpose of the present invention. This desired result is attained by depressing the crests of the marginal corrugations of the overlapping portion of sheet 6 along a line extending transversely of the corrugations, as illustrated in FIGS. 1, 4 and 5. It will be apparent from FIGS. 4 and 5 that by depressing the crests of the corrugations along a transverse line to a level substantially as shown, transversely extending ribs 12 are produced between adjacent valleys 13 of the corrugations. Such ribs, together with the depending valleys 13 penetrate into the underlying mastic when the overlapping margin is depressed by the holding nails driven through the overlapped sheets. The ribs 12, therefore, provide a barrier extending transversely of the corrugations which precludes the entrance of moisture into the building between the sheets.

25 The formation of these barrier ribs is produced by a stamping or rolling action applied by a suitable instrument adapted to form aligned depressions in the crests of the corrugations. By the formation of these depressed barrier ribs, an elongated discontinuous depression or shallow groove extending transversely of the corrugations is formed. This groove, which is distinctly apparent to the applicator, provides a nailing line along which the fastening nails may be driven in neat alignment, as distinguished from the haphazard arrangement which has heretofore prevailed.

30 It will be apparent from the foregoing that I have provided corrugated roofing and sheathing sheets, preferably in roll form, which can be economically manufactured and rapidly laid, and which by the provision of a sealing barrier insure against the entrance of moisture by capillary action or otherwise between the lapped sheets.

35 The specific embodiment of my invention here disclosed may be varied within considerable limits without exceeding the scope of my invention as defined in the following claims.

40 I claim:

45 1. A corrugated sheet for roofing or sheathing purposes having transversely disposed corrugations of sub-

stantial depth and width and marginal areas at the opposite edges of said sheet having transversely disposed minor corrugations of lesser depth and width than the major corrugations, a strip of plastic mastic sealing material extending transversely across the minor corrugations at one edge thereof, and a depression in the crest only of each of the minor corrugations at the other edge thereof with said depressions arranged in alignment transversely across the sheet and disposed intermediate the length of the minor corrugations at said other edge to provide a 10 single row of barrier sealing ribs disposed transversely of said last mentioned minor corrugations and penetrating the sealing material of an overlapped companion sheet to obstruct the passage of moisture between said sheets and to provide a transverse nail line for anchoring the overlapping sheets.

2. Corrugated building material comprising corrugated sheets having their marginal end portions in overlapped relation, each of said sheets having transversely disposed major corrugations of substantial depth and width and 20 marginal portions at the opposite ends having transversely disposed minor corrugations of less depth and

width than the major corrugations, one of said sheets provided with a strip of plastic mastic sealing material on and extending transversely of the minor corrugations of its overlapped marginal end portion and the other of said sheets provided on its overlapping marginal end portion with a single row of aligned barrier sealing ribs depressed from the crest only of the overlapping minor corrugations, said ribs extending transversely across the overlapping sheet and intermediate the length of its minor corrugations and embedded in the underlying sealing material of the overlapped marginal end portion to obstruct the passage of moisture between said sheets and to provide a transverse nail line for anchoring the overlapping sheets.
